WATER BACK FOR HOT AIR AND OTHER FURNACES

Filed Feb. 27. 1922

Joseph Hopfenbacher. INVENTORS
BY Charles H. Fischer.
Diedersheim & Fairbanks. ATTORNEYS.

UNITED STATES PATENT OFFICE.

JOSEPH HOPFENTHALER AND CHARLES H. FISCHER, OF PHILADELPHIA, PENNSYLVANIA.

WATER BACK FOR HOT-AIR AND OTHER FURNACES.

Application filed February 27, 1922. Serial No. 539,463.

To all whom it may concern:

Be it known that we, JOSEPH HOPFENTHALER and CHARLES H. FISCHER, citizens of the United States, residing in the city and county of Philadelphia, State of Pennsylvania, have invented a new and useful Water Back for Hot-Air and Other Furnaces, of which the following is a specification.

Our invention consists of a water back for a hot air and hot water heater, a furnace, or the like, the same being adapted to be supported on a member within the fire pot of the heater, etc., so as to relieve the water supply and outlet pipes of so supporting the water back.

The invention is satisfactorily illustrated in the accompanying drawing, but the important instrumentalities thereof may be varied, and so it is to be understood that the invention is not limited to the specific details shown and described, as long as they are within the spirit or scope of the claims.

Figure 1 represents a top or plan view of a water back embodying our invention.

Figure 2 represents a perspective view thereof partly broken away.

Figure 3 represents a vertical section on line 3—3, Figure 1.

Similar numerals of reference indicate corresponding parts in the figures.

Referring to the drawing.

1 designates the water back which comprises a hollow body formed of the front wall 2, the rear wall 3, the side walls 4, the bottom wall 5, the cap plate 6 at the top, the interior diaphragm 7 which depends from the underside of the cap plate to near the bottom of the body so as to form the passage 8 between the lower end of said diaphragm and the bottom 5 forming a communication between the opposite side portion of said body, the nipple 9 on the cap plate for the attachment of the pipe 10 which supplies water to the body between the opposite side portions of said body the nipple 11 on said cap plate opposite to nipple 9 for the attachment of the pipe 12 for the outlet of the hot water from the body to the place of service, said pipes 10 and 12 being shown dotted in Figure 1, and the flange 13, the latter being a rearward or outward extension of the cap plate 6.

It will be seen owing to the diaphragm

and passage 8 the water has a circuitous circulation through the body from its inlet to 55 the outlet when, as will be seen, the water descends from its inlet in one side portion of the body, flows through the passage 8, and enters the other side portion of the body and rises therein to its outlet, whereby it 60 is doubly-subjected, due to its two courses, to the heat of the furnace, the effect of which is evident.

On the interior of the wall 14 of the heater, etc., is the horizontally extending 65 shoulder 15 on which the flange 13 is seated and so the water back is firmly and properly supported on said flange suspended within the fire pot, and the pipes 10 and 12 are relieved of any material weight of the water 70 back, and the openings in the wall 14 through the upper part of which said pipes pass are not liable to be strained and enlarged by any downward pull of the water 75 back since such pull is imposed by the flange 13 on the shoulder 15 but as said pipes pass through the adjacent portion of the wall 14 above the water back they assist in retaining the latter against the wall 14 and so steady it in position.

Having thus described our invention what we claim as new and desire to secure by Letters Patent, is:—

1. A water back for a heater of the character stated having a vertically-disposed body, and a closing cap plate provided with a flange outwardly extended for contact with an offset shoulder within the furnace, there being a depending diaphragm within the body extending to nearly the bottom. 85 90

2. A water back for a heater comprising a hollow body, a cap plate forming the closure for the upper end thereof, said body having a depending diaphragm extended nearly to the bottom, and said cap plate 95 having a lateral flange projecting beyond the wall of the said body for seating on an offset shoulder member within the firepot of the heater whereby said water back is suspended within the firepot. 100

3. As an improved article of manufacture, a water back for a heater comprising a hollow body vertically elongated and having a cap plate constituting a closure for the upper end thereof and provided with a lateral flange, and a vertical diaphragm with- 105

in the body terminating below at a distance above the bottom of the body and depending from the cap plate.

4. As an improved article of manufacture, 5 a water back for a heater comprising a hollow body having a cap plate constituting a closure for the upper end thereof and provided with a lateral flange, said body

formed with a vertical diaphragm terminating at a distance from the bottom of the 10 body, said body being dependently supported and the cap plate having inlet and outlet nipples disposed upon opposite sides of said diaphragm.

JOSEPH HOPFENTHALER.
CHARLES H. FISCHER.
